WINDOW STRUCTURE AND OPERATING MEDIUM THEREFOR

Edward Y. Hashimoto, Wahiawa, Oahu,
Territory of Hawaii

Application October 31, 1950, Serial No. 193,192

2 Claims. (Cl. 268—25)

1

This invention relates to window structures, and more particularly to windows of the type having a plurality of horizontally pivoted window sections.

A main object of the invention is to provide a novel and improved window structure of the transom type, having a plurality of horizontally pivoted sections, said structure being simple in construction, being easy to operate, and involving relatively inexpensive parts.

A further object of the invention is to provide an improved window structure of the transom type which provides maximum light transmission and ventilation, which is dependable in operation, which is easy to install and to maintain, and which provides an attractive appearance.

Further objects and advantages of the invention will become apparent from the following description and claims, and from the accompanying drawings, wherein:

Figure 1 is a fragmentary front elevational view of a portion of a building showing the installation of an improved window structure according to the present invention;

Figure 2 is a vertical cross-sectional view taken on the line 2—2 of Figure 1;

Figure 3 is an enlarged cross-sectional detail view taken on line 3—3 of Figure 1;

Figure 4 is an enlarged cross-sectional detail view taken on line 4—4 of Figure 2;

Figure 5 is an enlarged cross-sectional detail view taken on line 5—5 of Figure 1;

Figure 6 is a cross-sectional view taken on line 6—6 of Figure 5;

Figure 7 is a perspective detail view of one of the window-pane-retaining clips employed in the improved window structure of Figures 1 to 6.

Referring to the drawings, 11 generally designates a frame, said frame being a portion of a building, and constituting the support and closure for a window or transom. The frame 11 includes vertical side members 12, 12', the intermediate vertical member 13, the horizontal top member 14, the sill structure 15, and the respective depending extensions of the vertical members 12', 12 and 13, shown respectively at 16, 17 and 18. The enclosure defined by the frame members 15, 16 and 18 may, for example, be a doorway, and the frame enclosure defined between the members 12' and 13 and 12 and 13 may be transom sections.

Secured to the opposite side surfaces of the intermediate vertical frame member 13 are the respective vertical guide strips 19 and 20, the strip

19 facing the vertical frame member 12', and the strip 20 facing the vertical frame member 12. Designated at 21 is a vertical guide strip secured to the inside surface of the member 12' and facing the guide strip 19. Similarly, secured to the inside surface of the vertical frame member 12 is a vertical guide strip 22 facing the guide strip 20. Each of said guide strips is formed at its forward portion with an inwardly projecting, vertical, hollow rib 23 having a flange portion 24 which overlies and is secured to the front surface of the adjacent vertical frame member. Each guide strip is formed at its rear portion with a forwardly facing, vertical channel 25. Slidably engaged in each vertical channel 25 is a rearwardly facing channel member 26 whose web portion is formed with the evenly spaced apertures 27 extending vertically for the entire length of the channel member. Designated at 28 are respective transparent window panes horizontally pivoted between the respective pairs of frame members 12, 13 and 13, 12'. Pivotedly secured to the respective opposing pairs of vertical ribs 23 are the respective opposing pairs of gear segments 29, 29, the teeth of said gears engaging in the apertures 27 of the respective channel members 26 slidably supported in the associated guide strips 21. As shown in Figures 1, 2 and 3, each window pane 28 is secured at its side margins to a respective pair of gear segments 29, 29. As shown in Figure 3, each gear segment 29 is formed at its rear portion with a depending bracket 30 integral with the gear segment, said bracket 30 having a flange 31 at its lower end. Each gear segment is likewise formed with the spaced lugs 32, 33 and 34, as shown in Figure 3, disposed forwardly of and parallel to the bracket element 30. Each window pane section 28 is installed with its side marginal portions received between the bracket elements 30 and the lugs 32, 33 and 34 associated with the respective gear members 29, the side marginal portions of the glass panes being clamped to the gear segments by spring keys 35 which are inserted between the forward surfaces of the window panes and the respective lugs 32, 33 and 34, as shown in Figure 3. Each key 35 comprises a strip of spring metal having an inwardly bent top flange 36 adapted to engage the top edge of the window pane, having the respective, mutually inclined sections 37, 38, as shown in Figure 7, having the U-bend 39 adjacent the section 38, and having the succeeding inclined sections 40 and 41, as illustrated in Figure 7. The key member 35 is adapted to be wedgingly received between the

glass pane and the respective lugs 32, 33 and 34, with the U-bend 39 lockingly engaged between the lugs 33 and 34, as shown in Figure 3. The end section 41 of the key member is bent outwardly, as shown at 42, to provide a cushioning element which is engageable against a stationary stop lug 43 provided on the hollow rib 23 of the associated vertical guide strip 19.

As shown in Figure 4, a horizontal bearing sleeve 44 is secured in the intermediate portion 10 of the vertical frame member 13 and rotatably mounted in the sleeve is a shaft 45 which has secured to its ends the respective sprocket gears 46, 46', which mesh with the apertures 27 of the respective slidable channel members 26 carried in the guide strips 19 and 20 on opposite sides of the member 13. The sprockets 46 and 46', together with the shaft 45, provide a mechanical coupling between the vertical channel members 26 on opposite sides of the frame member 13. It will also be apparent that vertical movement of the apertured channel members 26 causes the gear segments 29 to be rotated, whereby the transparent window panes 28 are similarly rotated. For example, in Figure 3, if the gear segments 29 are rotated counterclockwise responsive to downward movement of the apertured channels 26, the window panes 28 are rotated counterclockwise from their full line positions, as shown in Figure 3, to their dotted line positions, causing said window panes to be moved to open positions. Similarly, by moving the channel members 26 upwardly, the window panes may be rotated from their open positions to their closed positions shown in full lines in Figure 3. Movement of the window panes to their closed positions is cushioned by the engagement of the curved, resilient ends 42 of the clips 35 with the stationary stop lugs 43.

Designated at 47 is a horizontal crossbar connecting the members 17 and 18, as shown in Figure 1, and secured thereto is a bracket member 48 in which is rotatably mounted a worm 49 to the shaft of which is secured a crank handle 50. Journaled between the bracket 48 and a vertical guide strip 20', as shown in Figure 6, is a shaft member 51 extending transverse to the worm 49 and carrying a worm gear 52 which meshes with worm 49. The bracket member 20' is in vertical alignment with the guide strip 20 and slidably receives the apertured channel member 26 associated with said guide strip 20. Secured on the shaft 51 is a sprocket gear 53 which meshingly engages the apertured channel member 26, as shown in Figure 6. Therefore, when the crank handle 50 is rotated, the worm 49 rotates the shaft 51 and the gear 53 causes the apertured channel member 26 engaged thereby to move vertically. This causes the window panes 28 on both sides of the vertical frame member 13 to be rotated, inasmuch as the panes on opposite sides are mechanically coupled together by means of the shaft 45 and the sprockets 46 and 46' which engage the respective apertured, vertically slidable channel members on the opposite sides of the frame member 13.

From the foregoing description it will be apparent that all of the transparent window panes will be simultaneously rotated in response to rotation of the hand crank 50. Obviously, any number of window panes may be employed in the transom unit, and any number of sections may be employed, each section being coupled to an adjacent section by the use of a shaft similar to

shaft 45 and the sprockets 46 and 46' carried by said shaft.

While a specific embodiment of an improved window structure of the transom type has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. In a window structure, a frame having vertical side members, respective opposed pairs of parallel gear segments rotatably secured to the respective side members for rotation around respective vertically spaced horizontal axes, each horizontal axis being associated with one pair of opposed gear segments, a window panel disposed between each pair of gear segments, clamping means carried by the gear segments and clampingly engaging the respective side marginal portions of the window panels, respective vertical rack bars slidably carried by the respective side members and meshing with the gear segments, whereby vertical movement of the rack bars rotates the window panels, a horizontal shaft journaled to said frame adjacent one of the side members, a first gear on said shaft meshing with one of said vertical rack bars, a hand crank journaled to said frame, a second gear on said shaft, and a worm axially secured to said hand crank and meshing with said second gear, a second frame adjacent the first named frame and having parallel gear segments and meshing rack bars adjacent the sides of the frame, a second horizontal shaft, a gear segment on one end of said second shaft meshing with a rack bar of the first frame, and a second gear on the other end of said second shaft meshing with the adjacent rack bar of the second frame, whereby actuation of one window will actuate all.

2. In a window structure of the type having a plurality of frames arranged in adjacent side-by-side relation, each frame having a plurality of window panels pivotally mounted therein for rotation around respective vertically spaced horizontal axes, each frame having adjacent vertical side members, a gear segment carried by each window panel on said adjacent side members, respective vertical rack bars carried by the adjacent vertical side members of the frames and meshing with the gear segments therein, respective shafts extending through the side members between adjacent frames, and gears on the ends of the shafts meshing with the respective vertical rack bars in the adjacent frames, whereby all of the window panels may be simultaneously rotated by moving one of the rack bars vertically, and additional gear means meshing with one of said rack bars for raising said last named rack bar, and means for rotating said gear means.

EDWARD Y. HASHIMOTO.
